UNITED STATES PATENT OFFICE

2,351,129

ANCHOR STUD FOR ABRASIVE WHEELS

Rudolph Jockel, Chicago, Ill., assignor to Titan
Abrasive Company, a corporation of Illinois

Application January 9, 1943, Serial No. 471,908

6 Claims. (Cl. 51—209)

This invention relates to anchor studs for abrasive wheels and more especially to such a stud or fastening device adapted for attaching a molded abrasive wheel to a metal backing.

Among the features of my invention is the provision of means for fastening a stud to an abrasive wheel by strong and rugged attachment and yet permit very slight flexibility or bending of the stud without loosening the attachment.

Other features and advantages of the invention will appear more fully as I proceed with the specification.

In those forms of devices embodying the features of my invention, shown in the accompanying drawing, Figure 1 is a fragmentary view of the back of an abrasive wheel with a portion of the backing broken away; Figure 2 is a view taken as indicated by the line 2 of Figure 1; Figure 3 is a view similar to Figure 2 showing a modified form; Figure 4 is a view taken as indicated by the line 4 of Figure 3; Figure 5 is a view similar to Figure 3 showing another modified form; and Figure 6 is a view taken as indicated by the line 6 of Figure 5.

As shown in the drawing, 10 may indicate the metal backing for a molded abrasive wheel 11, for example, a wheel molded of granulated carborundum or other abrasive bonded by suitable cement such as Bakelite or resin, usually hardened by baking.

In order to attach the wheel 11 to the steel back 10 it is customary to provide the wheel with studs adapted to be inserted through holes in the back 10. My invention relates particularly to the manner of fastening such studs in the wheel itself.

In that form of device shown in Figure 2, a metal disk 12 with a flaring flange 12a is embedded in the wheel 11, with a nut 13 under the disk, that is, inside of the flange 12a. The outer surface of the disk 12 is preferably flush with the rear face 11a of the wheel. 14 indicates a bolt extending through a hole in the back 10 and threaded into the nut 13, such bolt, therefore, serving as a stud to hold the wheel to the back. The bolt 14 is provided with the usual head 14a.

The sheet metal disk 12 is preferably thin enough so that it has a very slight flexibility. This will permit a certain amount of bending or misalignment of the bolt 14 with a consequent certain amount of rocking of the nut 13 in the wheel 11 without permitting the same to become entirely loosened. It will be seen that even though the disk portion 12 of the member em-

bedded in the wheel 11 flexes or bends slightly, the flared flange 12a will always retain a firm anchorage in the wheel 11 and thus prevent removal of the head 13 from the wheel even though such nut becomes slightly loosened in the wheel material. The diameter of the flange 12a is enough larger than the diameter of the nut 13 so that any loosening or rocking of the nut 13 in the wheel 11 with consequent loosening of the wheel material about the nut 13 will not affect the wheel material which anchors the flange 12a.

The construction shown in Figure 3 is substantially the same as that shown in Figure 2 except that a stud 114 is employed instead of a bolt 14. In this case the head 113 on the stud 114 serves the same purpose as the nut 13 in the other device. In the device of Figure 2 the nut 13 serves as a head for the bolt or stud 14. Here the disk 112 with the flaring flange 112a corresponds to the disk 12 with the flaring flange 12a.

The device shown in Figures 5 and 6 is substantially the same as that shown in Figure 2, the disk 212 with the flaring flange 212a corresponding to the disk 12 with the flaring flange 12a; but as here shown the flange 12a is corrugated as indicated by 212b (see Figure 6) in order to give a better anchorage in the wheel material.

While I have shown and described certain embodiments of my invention, it is to be understood that it is capable of many modifications. Changes, therefore, in the construction and arrangement may be made without departing from the spirit and scope of the invention as disclosed in the appended claims, in which it is my intention to claim all novelty inherent in my invention as broadly as permissible, in view of the prior art.

What I claim as new and desire to secure by Letters Patent is:

40. 1. In combination with a cast abrasive wheel, a perforated sheet metal cup with its flared flange embedded in said wheel, and a stud projecting from said wheel through said perforation, said stud having a head within the cup embedded in the wheel.

45. 2. In combination with a cast abrasive wheel, a perforated sheet metal cup with its flared flange embedded in said wheel, said cup lying substantially flush with the rear face of the wheel, and a stud projecting from said wheel through said perforation, said stud having a head within the cup embedded in the wheel.

50. 3. In combination with a cast abrasive wheel, a perforated flexible sheet metal cup with its flared flange embedded in said wheel, and a stud

55. though the disk portion 12 of the member em-

projecting from said wheel through said perforation, said stud having a head within the cup embedded in the wheel.

4. In combination with a cast abrasive wheel, a perforated flexible sheet metal cup with its flared flange embedded in said wheel, said cup lying substantially flush with the rear face of the wheel, and a stud projecting from said wheel

through said perforation, said stud having a head within the cup embedded in the wheel.

5. A device as claimed in claim 1, in which the flange of the cup is corrugated.

6. A device as claimed in claim 2, in which the flange of the cup is corrugated.

RUDOLPH JOCKEL.
